[57] CLAIM

The ornamental design for a portable electric blower with a dust collector, as shown and described.

DESCRIPTION

FIG. 1 is a perspective view of an embodiment of a portable electric blower with a dust collector showing our new design;

FIG. 2 is another perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.

The broken lines showing of a cord, dust bag and fan in FIGS. 2 and 7 are for illustrative purposes only and forms no part of the claimed design.
